CLAIM

The ornamental design for a medical injector, as shown and described.

DESCRIPTION

The patent or application file contains at least one drawing executed in color. Copies of this patent or patent publication with color drawings(s) will be provided by the Office upon request and payment of the necessary fee.

FIG. 1 is a perspective view of a first embodiment of the medical injector without a cap.

FIG. 2 is front view thereof.

FIG. 3 is a back view thereof.

FIG. 4 is left side view thereof.

FIG. 5 is right side view thereof.

FIG. 6 is top view thereof.

FIG. 7 is bottom view thereof.

FIG. 8 is a perspective view of a second embodiment of the medical injector without a cap.

FIG. 9 is front view thereof.

FIG. 10 is a back view thereof.

FIG. 11 is left side view thereof.

FIG. 12 is right side view thereof.

FIG. 13 is top view thereof.

FIG. 14 is bottom view thereof.

FIG. 15 is a perspective view of a third embodiment of the medical injector without a cap.

FIG. 16 is front view thereof.

FIG. 17 is a back view thereof.

(Continued)

FIG. 18 is left side view thereof.
 FIG. 19 is right side view thereof.
 FIG. 20 is top view thereof.
 FIG. 21 is bottom view thereof.
 FIG. 22 is a perspective view of a fourth embodiment of the medical injector without a cap.
 FIG. 23 is front view thereof.
 FIG. 24 is a back view thereof.
 FIG. 25 is left side view thereof.
 FIG. 26 is right side view thereof.
 FIG. 27 is top view thereof; and,
 FIG. 28 is bottom view thereof.
